CLAIM

The ornamental design for a display screen with graphical user interface, as shown and described.

DESCRIPTION

FIG. 1 is a front view of a first image in a sequence for a display screen with a graphical user interface showing our new design;

FIG. 2 is a second image thereof;

FIG. 3 is a third image thereof;

FIG. 4 is a fourth image thereof;

FIG. 5 is a front view of a first image in a sequence for a display screen with a graphical user interface, according to a second embodiment;

FIG. 6 is a second image thereof;

FIG. 7 is a third image thereof; and,

FIG. 8 is a fourth image thereof.

The appearance of the graphical user interface transitions sequentially between the images shown in FIGS. 1-4 and 5-8. The process or period in which one image transitions to another forms no part of the claimed design.

The broken lines illustrate portions of the article, and form no part of the claimed design. The dot-dash broken lines illustrate a boundary of the claimed design; the dot-dash lines form no part of the claimed design.
